ATTORNEY.

UNITED STATES PATENT OFFICE

EDWARD P. GRISHAM, OF ST. LOUIS, MISSOURI

VENTILATING APPARATUS

Application filed October 1, 1928. Serial No. 309,493.

This invention relates to ventilating apparatus and has as its general object to provide an apparatus which may be readily installed in hotel and other rooms and will serve effectively to ventilate the room in which it is installed.

Another object of the invention is to provide a ventilating apparatus which will embody such an arrangement of its component parts that it may be caused to have a highly attractive appearance thus providing for ventilation of the room in which it is installed without the use of unsightly ventilator gratings installed in the walls of a room or other ventilating means presenting an unsightly appearance.

Another object of the invention is to provide an arrangement whereby the ventilating means may be combined with illuminating means so that the structure, as a whole, will present the appearance of a floor or table lamp as well as serving as such in addition to operating as a ventilating means.

While the accompanying drawings and the description which is to follow, constitute a disclosure of the preferred embodiment of the invention, it will be understood that various changes may be made within the scope of what is claimed.

30 In the accompanying drawings:

Figure 1 is a view in elevation of one form of ventilating apparatus embodying the invention, the same being illustrated as installed in a room and the room being shown in section;

Figure 2 is a horizontal sectional view taken substantially on the line 2—2 of Figure 1 looking in the direction indicated by the arrows.

40 The apparatus shown in the drawings is designed to operate in a manner to draw fresh air from the exterior of the building into the room to be ventilated and to deliver the air in a manner to effect the desired ventilation of the room and as illustrated in these figures the apparatus includes a hollow substantially cylindrical base 1 which may be of sheet metal or any other material found suitable for the purpose and which may be ornamented in any desired manner, the base being ar-

ranged upon the floor of the room 2 in which the apparatus is installed. A tubular standard 3 is mounted at its lower end in the top of the base 1 and extends vertically from the central portion of the said base and nearly 55 to the ceiling of the room, any suitable ornamental braces 5 being provided for bracing the standard with respect to the base as shown in Figure 1 of the drawings. In the illustrated embodiment, a cluster of electric light 60 bulbs 6 are installed in sockets 7 supported at the outer ends of tubular arms 8 which radiate from the standard 3 at a suitably elevated point corresponding substantially to the height of the ordinary electric floor lamp 65 and the standard 3 is extended above the bracket members or arms 8 and a shade 9 is preferably mounted upon the standard and surrounds the cluster of bulbs 6, an inverted 70 substantially conical spreader 10 being 75 mounted upon the upper end of the standard with its major open end presented toward the ceiling 4 but spaced from the same as shown in Figure 1.

As shown in the drawings a rotary air compressor 11 is mounted within the base 1 and the lower end of the tubular standard 3 is fitted into the outlet of the compressor casing, an electric motor 12 being likewise arranged within the base 1 and a conduit 13 being arranged beneath the floor of the room and having a branch extending upwardly and a short distance into the base 1 to permit of the conductor wire 14 which supplies the current, being connected with the motor 80 85 12, a branch 15 being led from this wire upwardly through the standard 3 to the sockets for the electric light bulbs 6.

The numeral 16 indicates an air conducting pipe one end of which is led into the base 1 and connected with the intake of the compressor casing 11, the other end of the pipe being placed in communication with the atmosphere exteriorly of the room in which the apparatus is installed by being 90 led to one of the windows of the room as shown in Figure 1 or in any other convenient manner.

From the foregoing description of the invention it will be understood that when the 10

motor 12 is energized and the compressor 11 is driven thereby, a strong current of air will be induced through the conducting pipe 16 as indicated by the arrows in Figure 1 and delivered through the tubular standard 3 in a stream directed upwardly against the ceiling 4 and through the open major or upper end of the spreader 10, the blast of air being broken up and caused to spread in all directions, upon striking the ceiling surface, as indicated by the arrows in the said Figure 1. In this manner fresh air is supplied to the room and caused to circulate therein thus keeping the room well ventilated and suitably cooled. It will be understood that any suitable switch (not shown) may be employed for controlling the supply of current to the motor 12 independently of the supply to the light bulbs 6 and it will also be understood that the standard 3 will be of sufficient internal diameter to permit of the conductor wires 15 being led therethrough without materially interfering with the flow of air under pressure through the standard.

26 Having thus described the invention, what I claim is:

Ventilating apparatus comprising a hollow base, a rotary air compressor housed within the base, motor means for driving said compressor also housed within the base, the compressor including a casing having an inlet and an outlet, a tubular air conducting standard having its lower end extending into the base and in communication with the outlet of the compressor casing, an inverted conical distributor mounted upon the upper end of the said standard whereby to be presented toward the ceiling of a room in which the apparatus is installed, and a fresh air intake pipe in communication with the inlet of the compressor.

In testimony whereof I affix my signature.

EDWARD P. GRISHAM.
